CLAIM

The ornamental design for an access control interface, as shown and described.

DESCRIPTION

FIG. 1 is a front elevational view of our design for an access control interface;

FIG. 2 is a right-side elevational view thereof, the left-side (not shown) being a mirror image thereof; and,

FIG. 3 is a top plan view thereof, the bottom (not shown) being a mirror image thereof.

The rear (not shown) forms no part of the claimed design.
